CLAIM

The ornamental design for a universal loudspeaker mounting adapter, as shown and described.

DESCRIPTION

FIG. 1 is a right front perspective view of the universal loudspeaker mounting adapter showing our new design;

FIG. 2 is a left rear perspective view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a left side elevational view thereof; and,

FIG. 8 is a right side elevational view thereof.

The broken lines illustrate portions of the universal loudspeaker mounting adapter that form no part of the claimed design.
